[57] CLAIM

The ornamental design of a fuel oil burner, as shown and described.

DESCRIPTION

FIG. 1 is a perspective view of the fuel oil burner according to the present invention and showing the top and front and left side elevations;

FIG. 2 is a front elevational view of the fuel oil burner according to the present invention;

FIG. 3 is a rear elevational view of the fuel oil burner according to the present invention;

FIG. 4 is a left side elevational view of the fuel oil burner according to the present invention;

FIG. 5 is a right side elevational view of the fuel oil burner according to the present invention;

FIG. 6 is a top plan view of the fuel oil burner according to the present invention;

FIG. 7 is a bottom plan view of the fuel oil burner according to the present invention; and,

FIG. 8 is a perspective view of the fuel oil burner according to the present invention as seen from the rear and bottom of FIG. 1.

FIG. 1

FIG. 2

FIG. 3

FIG. 4

FIG. 5

FIG. 6

FIG. 8
